UNITED STATES PATENT OFFICE.

ADOLPH M. HOLSTEIN, OF SYRACUSE, NEW YORK.

DESIGN FOR A MANUFACTURED PLAQUE OR SIMILAR FIGURE FOR FURNITURE,
CASKETS, AND BUILDING WALLS AND CEILINGS.

52,535.

Specification for Design.

Patented Oct. 8, 1918.

Application filed April 4, 1917. Serial No. 159,797. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for a Manufactured Plaque or Similar Figure for Furniture, Caskets, and Building Walls and Ceilings, of which the following is a specification, reference being had to the accompanying drawing, forming a part hereof.

The design comprehends a manufactured plaque or similar figure for furniture, caskets and building walls and ceilings repre-

senting a body of water bearing aquatic plants and from which arises hillock-like land in association with a cherry tree; featuring an element of Asiatic scenery.

I claim:

The ornamental design for a manufactured plaque or similar figure for furniture, caskets, and building walls and ceilings, substantially as shown and described.

In testimony whereof, I have hereunto signed my name at Syracuse, in the county of Onondaga, and State of New York, this 27th day of March, 1917.

ADOLPH M. HOLSTEIN.
